United States Patent Office

Des. 175,356
Patented Aug. 16, 1955

175,356

ADDING MACHINE

Paul M. Koons, Dayton, Ohio, assignor to The National
Cash Register Company, Dayton, Ohio, a corporation
of Maryland

Application April 19, 1954, Serial No. 30,093

Term of patent 14 years

(Cl. D64—11).

Des. 175,356

PAGE 2

FIG. 2

Fig. 1 is a front perspective view of an adding machine showing my new design;

Fig. 2 is a rear perspective view thereof; and

Fig. 3 is a side elevational view thereof, the side opposite thereto being substantially the same in appearance.

The roll of tape shown in dotted lines on the drawing is for illustrative purposes only.

I claim:

The ornamental design for an adding machine, as shown and described.
